Patented Oct. 5, 1976

241,754

CIGARETTE OR CIGAR PACKAGE HOLSTER

Dennis R. Halaszynski, Sr., 2609 Bunker St.,
McKeesport, Pa. 15132

Filed Mar. 3, 1975, Ser. No. 555,175

Term of patent 14 years

Int. Cl. D27—06

Fig. 1

U.S. Cl. D27—49

Fig. 2

Fig. 3

Fig. 4

Fig. 5

FIG. 1 is a perspective view of a cigarette or cigar package holster showing my new design;

FIG. 2 is a left side elevational view thereof;

FIG. 3 is a rear elevational view thereof with the ends of the supporting strap disconnected;

FIG. 4 is a top plan view thereof; and

FIG. 5 is a bottom plan view thereof.

The supporting strap which is adapted to encircle the leg adjacent the ankle has been omitted from FIGS. 2, 4 and 5 for clarity.

I claim:

The ornamental design for a cigarette or cigar package holster, as shown and described.
